EXTERNAL FORM SPREADER

Filed June 20, 1935

UNITED STATES PATENT OFFICE

2,096,868

EXTERNAL FORM SPREADER

Henry Herbert Toogood, Los Angeles, Calif.

Application June 20, 1935, Serial No. 27,600

8 Claims. (Cl. 25—131)

This invention relates to concrete wall constructions and more particularly to a means for maintaining the concrete forms in spaced apart relation.

5 An object of this invention is to provide a spreader which is so constructed that it may be applied externally during the setting up of the forms and may be removed in the same manner after the concrete has poured and the wet concrete reaches the height of the spreader so that when the forms are removed the exterior surface of the concrete will not have to be surfaced in order to cover up the holes formed by the spreader.

15 A further object of this invention is to provide an externally applied spreader which is so constructed that it can be secured to either the waler, stud or sheathing and, if desired, the spreader can be so constructed as to be adjustable 20 as to length so as to take care of any variations in the configuration of the form.

The above and various other objects and advantages of this invention will in part be described in, and in part be understood from the 25 following detail description of the present preferred embodiment, the same being illustrated in the accompanying drawing, wherein:

Figure 1 is a top plan of a spreader constructed according to an embodiment of this invention, 30 showing the spreader in applied position on the concrete form shown in fragmentary sectional form.

Figure 2 is a view similar to Figure 1 showing the fixed end of the spreader secured to a waler.

35 Figure 3 is a fragmentary side elevation of the spreader.

Figure 4 is a fragmentary sectional view partly in elevation of a modified form of this spreader.

Figure 5 is a top plan of a further embodiment 40 of this invention.

Referring to the drawing wherein like numerals of reference designate corresponding parts throughout the several views, the numeral 10 designates generally one side of a form and the 45 numeral 11 designates an opposing form which is spaced apart from the form 10. Each form is of substantially similar construction comprising a sheathing 12 to which studs 13 are secured, the studs being substantially vertical or at right 50 angles to the lengths of the boards forming the sheathing 12. In order to further reinforce the forms, walers 14 are secured to the outer edges of the studs 13 and at right angles to the lengths of the studs 13. These forms 10 and 11 are of 55 conventional construction and are here shown as

only one type of concrete form construction with which the hereinbefore described spreader constructions may be applied.

It has been the practice in building constructions where walls are formed of concrete to insert between the forms spreading members constructed either of wood or metal and it has also been the practice to leave these spreader members embedded in the concrete wall or to withdraw the spreaders after the concrete has set and then 10 plug up the holes formed by removal of the spreaders. In the latter case it is necessary to go over the surface of the concrete by erecting scaffolding and in many instances, the spreaders are damaged in the removal thereof or the forms 15 are injured by contact of piercing points carried by the spreaders. It is, therefore, an object of this invention to provide a spreader to hold the forms 10 and 11 in spaced apart relation which can be applied from the exterior of one or the 20 other of the forms and which can be removed during the pouring of the concrete, that is, when the level of the concrete reaches the spreaders or while the concrete is still in liquid form.

In this manner the moist concrete will fill up 25 the holes formed by removal of the spreaders and the exterior surface of the wall will not show any holes requiring filling up after the concrete has set. At the present time it is deemed desirable to form concrete walls of monolithic construction and to leave the surface of the walls 30 in their original condition, this being particularly desirable in regions subjected to earthquakes, or like tremors.

In order, therefore, to provide a spreader which 35 will accomplish the results hereinbefore described, I have provided an elongated bar 15 which may be of desired configuration transversely, that is, either round, rectangular or any other suitable configuration. The inner end 16 of this spreader rod 15 is adapted to abut against the inside of 40 the face form 11 and is adapted to project through a hole 17 provided in the sheathing 12 of the form 10.

The outer end of the rod 15 is secured to an 45 attaching plate, as by welding 19 or the like. This attaching plate 18 extends parallel to the longitudinal axis of the rod 15 and is of a width in excess of the bottom of said rod and is provided in its excess marginal portions and preferably on both sides of the rod, with holes 21 50 through which fastening devices 22 in the form of double-headed nails, are adapted to extend to secure the plate to a stud or waler. The inner end 20 of the plate 18 forms an abutment adapted 55 to engage against the outer side of the sheathing 55

12 or stud 13, and the plate 18 projects beyond the outer end of the spreader rod 15 and this outer end is bent upon itself, as at 23, so as to form a hook which may be engaged by a suitable 5 tool so that when the nails 22 are withdrawn, the implement or tool may be engaged with the hook portion 23 and the rod 15 pulled out from between the forms.

As shown in Figure 1, the plate 18 is secured 10 to a stud 13 but, if desired, the plate 18 may be secured to a waler 14, as shown in Figure 2, in which event the rod 15 will, of course, be made longer so that when it is in applied position the two forms 10 and 11 will be maintained in the 15 predetermined spaced apart relation. If desired, the spreader member comprising the rod 15 and the plate 18 may be formed in a slightly different manner, that is, the abutment 20 may be made integral with the rod 15.

20 In Figure 4, there is shown a modified form of this invention where the spreader rod 15a is adapted to be secured to the sheathing 12a. In this construction, the abutment is formed by a substantially L-shaped plate 18a which has one leg 24 welded as by welding 25 to the rod 15a and the other leg 26 is provided with suitable holes 17 to receive nails or fastening devices 28.

In Figure 5 there is shown a further form of 30 this invention where the spreader rod 15b is threaded, as at 29, for a considerable portion of its length and the outer end of the rod 15b is provided with a head 30 which may be engaged by a wrench or other tool. A cylindrical interiorly threaded member 31 is threaded on to the rod 15b exteriorly of the sheathing 12b and a base plate 18b provided with suitable holes 21b is fastened to the cylindrical nut 31 as by welding or other suitable means. The plate 18b in this instance is secured by nails or fastening devices 32 to a stud 13b. In the use 40 of the spreader 15b the rod is adjusted so that the inner end 16b will engage the opposite form and when the two forms are in the desired spaced apart relation a lock nut 33 is tightened 45 and engages against the outer end of the fixed nut 31 secured to the plate 18b.

In the use and operation of the spreader hereinbefore described wherein the spreader as shown in Figure 1 is used, the sheathing 12 is drilled 50 with the desired size hole and the abutment 20 carried by the plate 18 is adapted to engage against the outer side of the sheathing 12. The inner end 16 of the spreader 15 will contact with the inner side of the form 11 and the nails 55 or fastening devices 22 will be secured to either the stud 13 or the waler 14. During the pouring of the concrete, the spreaders will be left in applied position until the moist concrete reaches substantially the level of the spreader 15 whereupon the nails 22 will be withdrawn and a suitable tool or implement applied to the hook 23 so as to pull the spreaders 15 out of the sheathing 12.

It will, of course, be understood that these 65 spreaders 15 may be left in the form until they are substantially embedded in the concrete and then removed with the concrete still in a sufficiently moist condition so that the concrete will fill up the holes formed by the withdrawal of the spreaders 15. These spreaders will not be injured in any manner by their application to the forms and can, therefore, be used over and over again and, where desired, in the event the 70 spreader is used to maintain forms in spaced

apart relation with the space less than the distance between the abutment 20 and the inner end 16 of the rod 15, allowance being made for the thickness of the sheathing 12, the plate 18 may be moved outwardly on the face of a stud 5 13 or waler 14 in which case the abutment 20 will not contact with the outer side of the sheathing 12. It will be apparent from this that one particular length of spreader may be used for different widths of walls.

10 I claim:—

1. A form spreader comprising a relatively rigid elongated bar adapted to extend freely through one wall of a form into abutting relation with the opposite wall of the form, a plate 15 fixed to said bar at one end thereof and in overlapping relation to said end, said plate extending parallel to the longitudinal axis of the bar whereby its inner end will form an abutment for the purpose described, said plate being of a width in excess of the diameter of said bar and formed on opposite sides of said bar with holes for the reception of fastening devices.

2. A form spreader comprising a relatively rigid elongated bar adapted to extend freely 20 through one wall of a form into abutting relation with the opposite wall of the form, a plate fixed to said bar at one end thereof and in overlapping relation to said end, said plate extending parallel to the longitudinal axis of the bar 25 whereby its inner end will form an abutment for the purpose described, said plate being of a width in excess of the diameter of said bar and formed on opposite sides of said bar with holes for the reception of fastening devices, the outer end of 30 said plate being turned upon itself to form a hook.

3. A form spreader comprising a substantially rigid elongated bar adapted to extend through 35 one wall of a concrete form with one end thereof abutting against the inside face of the opposite wall of the form, and a combined abutment and bar holding plate welded to a side of the bar adjacent the other or outer end, said plate being provided with holes on opposite sides of the bar and having a portion thereof projecting beyond 40 the outer end of the bar and terminating in a 45 reverted hook-shaped end confronting the outer end of the bar.

4. A form spreader comprising a substantially rigid elongated bar adapted to extend through 50 one wall of a concrete form with one end thereof of abutting against the inside face of the opposite wall of the form, and a combined abutment and bar holding plate welded to said bar adjacent the other or outer end, said plate being provided with 55 holes therethrough to receive fastening devices whereby the plate may be secured flat against a portion of the form in parallel relation to said bar.

5. A form spreader comprising a substantially 60 rigid elongated bar adapted to extend through one wall of a concrete form with one end thereof abutting against the inside face of the opposite wall of the form, and a combined abutment and bar holding plate fixed to a side of the bar adjacent the other or outer end, said plate being provided 65 with holes to receive fastening devices whereby said plate may be detachably secured to said one wall of the form.

6. A form spreader comprising a substantially 70 rigid elongated bar adapted to extend through one wall of a concrete form with one end thereof of abutting against the inside face of the opposite wall of the form, and a combined abutment and bar holding plate having one side thereof 75

fixed to a side of the bar adjacent the other or outer end thereof, and a lateral extension integral with said plate, said extension being provided with holes to receive fastening devices to secure said extension in face abutting relation to a side of the form.

7. A form spreader comprising a substantially rigid elongated bar adapted to extend through one wall of a concrete form with one end thereof abutting against the inside face of the opposite wall of the form, and a combined abutment and bar holding plate having one side thereof fixed to a side of the bar adjacent the other or outer end thereof, and a right angularly disposed extension integral with the inner end of said plate,

said extension being provided with holes to receive fastening devices to secure said extension in face abutting relation to a side of the form.

8. A form spreader comprising a substantially rigid elongated bar adapted to extend through one wall of a concrete form with one end thereof abutting against the inside face of the opposite wall of the form, and a combined abutment and bar holding plate fixed to said bar and extending laterally thereof at right angles to the length of the bar, said plate being provided with holes to receive fastening devices to secure said plate in face abutting relation to a side of the form.
